UNITED STATES PATENT OFFICE.

LOUIS WILHELM, OF WORCESTER, MASSACHUSETTS, ASSIGNOR OF ONE-HALF TO FREDERICK A. STEVENS, OF PROVIDENCE, RHODE ISLAND.

METHOD OF MAKING BIFOCAL LENSES.

No. 901,576.

Specification of Letters Patent.

Patented Oct. 20, 1908.

Application filed February 18, 1908. Serial No. 416,622.

To all whom it may concern:

Be it known that I, LOUIS WILHELM, a citizen of the United States, residing at Worcester, in the county of Worcester and 5 State of Massachusetts, have invented certain new and useful Improvements in Methods of Making Bifocal Lenses, of which the following is a specification.

My invention relates to bi-focal lenses 10 wherein two component lens pieces or blanks are united into a composite or unitary whole by fusing, and has for its essential objects the avoidance of scratching the said blanks during the progress of construction 15 whereby the visual field is marred; to avoid imperfections resultant upon the formation of bubbles intermediate the contiguous blank surfaces during the welding action; to accomplish the fusion by means which shall 20 not subject the component lens parts to danger of fracture in grinding the final product; to insure against dislocation or derangement of the component blanks during 25 fusion; and to reduce the expense of the fusing operation.

My invention consists, therefore, in the process or method of uniting the main and auxiliary lens blanks hereinafter set forth and claimed.

30 In the drawings, which constitute a part of this specification, Figure 1 is a plan view of a lens blank after the molding operation. Fig. 2, a like view of the auxiliary blank. Fig. 3, a section of the main blank on line 35 $\alpha\alpha$ of Fig. 1, showing in section the auxiliary blank in position for fusing. Fig. 4, a like section of the parts after fusing. Fig. 5, a similar section of the same after grinding. Fig. 6, a plan of the completed lens. 40 Fig. 7, a sectional view of a modified form of lens parts preparatory to fusing, and Fig. 8, a plan view of a second modified form of the main lens blank.

Like reference characters indicate like 45 parts throughout the views.

In detail my process consists in molding the main lens blank, A, which may be concave, convex, or plano-convex, with one or more integral projections, B, and a concave 50 cavity, C, intermediate the projections, upon its face. In this instance, the projections are three in number. The surface of the cavity, C, is smoothed by grinding. The

projections are adjacent the margin of the cavity and equidistant therefrom. Upon the 55 tops of the projections is placed an auxiliary blank, D, as shown in Fig. 3, composed of glass having a different refractive index, and fusible at a lower degree than the glass in blank, A. To the parts thus assembled, 60 heat is applied in a muffle or by any other convenient means. The projections separate the lower surface of the blank, D, from the surface of the cavity, C, until the blank, D, becomes plastic, sinks into the cavity, C, and 65 becomes fused sufficiently to become perfectly welded with the blank, A, as shown in Fig. 4. The portions of the blank, D, which extend above the blank, A, and the projections, B, are next ground away, and the surface of the completed lens polished. If preferred, the projections may be shouldered or 70 irregular, B', as shown in Fig. 7, adapted to form a seat for the auxiliary lens. In Fig. 8, the projections, B'', are of arcuate form. 75 It is, however, essential that the projections under all circumstances be integral with the blank, A.

What I claim is,

1. The method of making bi-focal lenses 80 which consists in molding glass to form a blank with integral projections and a cavity upon its surface, placing a fusible disk upon the projections, and subjecting the parts to a welding heat to unite disk and blank. 85

2. The method of making bi-focal lenses which consists in molding glass to form a blank with circularly disposed integral projections upon its surface and a cavity in the 90 surface of the blank within and concentric to the projections, placing a disk upon the projections, and submitting the whole to heat whereby the disk sinks upon and is united with the blank.

3. The method of making bi-focal lenses 95 which consists in molding glass to form a blank with integral projections upon its surface, forming a cavity in the surface of the blank within and concentric to the projections, placing a disk upon the projections, 100 submitting the assembled parts to heat to precipitate the disk into the cavity and adhere to the blank, and grinding and polishing the completed lens.

4. The method of making bi-focal lenses 105 which consists in molding a blank with a

cavity and integral projections around the cavity, next grinding out the cavity, then placing a fusible disk upon the projections, and finally subjecting the parts to a welding heat to unite the parts.

5. The method of making bi-focal lenses which consists in molding a blank with integral projections upon its surface, grinding a cavity in the surface of the blank within the

projections, and subjecting the parts to a 10, welding heat to unite the disk and blank.

In testimony whereof I have affixed my signature in presence of two witnesses.

LOUIS WILHELM.
